UNITED STATES PATENT OFFICE.

HARRIET LYONS REDMOND, OF BOSTON, MASSACHUSETTS, ASSIGNOR TO THE WILLIAM CARTER COMPANY, OF NEEDHAM HEIGHTS, MASSACHUSETTS, A CORPORATION OF MASSACHUSETTS.

INFANT'S BAND.

Application filed July 22, 1921. Serial No. 486,670.

To all whom it may concern:

Be it known that HARRIET LYONS REDMOND, a citizen of the United States, and a resident of Boston, in the county of Suffolk 5 and State of Massachusetts, has invented an Improvement in Infants' Bands, of which the following description, in connection with the accompanying drawings, is a specification, like characters on the drawings representing like parts.

This invention relates to infants' bands, and particularly to infants' bands for use in cases of umbilical hernia or like difficulties, it being an improvement upon the construction 15 shown in my co-pending application Serial No. 475,808, filed June 7, 1921.

In order that the principle of the invention may be readily understood, I have disclosed a single embodiment thereof in the 20 accompanying drawing wherein,—

Fig. 1 is a plan view of the band when it is opened out or unfolded and looking at the inner face thereof, a portion of the band being broken away to show the tape structure;

Fig. 2 is a front elevation of the band when in its folded condition;

Fig. 3 is a rear elevation thereof in its folded condition; and

Fig. 4 is a vertical sectional view upon the line 4—4 of Fig. 2.

Referring more particularly to the drawing, the band in its entirety is represented at 1. It may be of any suitable material, but it 35 is preferably knitted and desirably the wales 2 extend lengthwise of the band, so that the band has but little elasticity or stretch lengthwise, but is relatively elastic transversely.

While the band may be provided with any suitable means for securing it in position after it has been wrapped about the infant, I have in the present instance shown a pin 3 adapted to be passed through the end of the 45 band and the underlying part thereof. I have also provided the band with a tape or strap 4 which may be of any suitable material, but is preferably woven, so as to give substantial body and firmly to hold the pins

5 which are adapted to be used for securing the folded portion of the body of the band thereto. The tape or strap 4 is attached to the band 1, preferably only at the upper and lower edges of the latter and so that the end 55 of the band, when the latter is folded, may

be passed under the tape or strap 4, as shown in Fig. 3, after which the extreme end of the band is folded in front, as indicated in Fig. 2, and there secured by the pin 3. Preferably I secure a reenforcing woven tape or 60 strap 4' to the face of the band 2 beneath the tape or strap 4, so that the securing means hereinbefore referred to may be passed through both tapes 4, 4', as well as 65 through the end of the band.

Desirably the band is elastically reenforced or protected at the edge 6 throughout its entire extent and including the ends of the tapes or straps 4, 4' and in any suitable manner, as by an elastic seaming or other 70 similar sewing operation. Because of this construction, the edge of the band is of substantially the same degree of elasticity as the body thereof.

In order to adapt the band for its preferred use in cases of umbilical hernia or the like, I provide a pocket 7 at a suitable point. While the pocket may be formed in any suitable way, I desirably secure to the inner 75 face of the band a piece of knitted material, the wales whereof run at right angles to the direction of the wales in the body of the garment, thus making said pocket laterally expandable for the reception of its contents, the 80 said pocket being secured by a line of elastic 85 stitches 8 or otherwise to the body of the band, except along the upper edge, which is left open for the insertion of suitable material, such, for example, as cotton batting and a small weight or metal disk.

The band can be secured as tightly as desired, since the several pins may be inserted at suitable points, and thus the band tightly binds the infant and serves its intended 90 function.

The band is intended to be placed next the skin beneath the usual shirt or undergarment, and is not intended to have a diaper or any part attached to it. Thus it does not become displaced and is not open to the objections that arise in the case of a band forming a part of or attached to the shirt or undergarment and to which the diaper is intended to be attached.

It will be noted that the band 1 is somewhat tapering in shape and that the tape or strap 4 is attached to the band at or near the larger end, thus permitting the smaller end of the band to be passed under said tape or strap.

Having thus described one illustrative embodiment of my invention, I desire it to be understood that although specific terms are employed, they are used in a generic and descriptive sense and not for purposes of limitation, the scope of the invention being set forth in the following claim.

Claim.

An infant's or like band comprising an unslotted strip of knitted material having an unbroken contour slightly tapering substantially from end to end thereby to provide relatively wide and narrow ends respectively, a transverse woven tape stitched upon the outer face of said band adjacent the wider end only thereof, a second woven tape superimposed upon said first mentioned

tape, elastic seaming extending continuously about the edge of the band including the ends of said tapes and constituting securing means for attaching said superimposed tape at opposite ends only of the tape, and a pocket of knitted fabric elastically seamed upon the inner face of the band near the wider end thereof for the reception of cotton batting or other material and adapted to rest against the part to be treated, the wales of said band and of said pocket extending at substantially right angles to each other.

In testimony whereof, I have signed my name to this specification.

HARRIET LYONS REDMOND.
